DESIGN FOR A DECORATIVE NAIL

Harry Chalfin, New York, N. Y.

Application July 12, 1939, Serial No. 85,956

Term of patent 3½ years

To all whom it may concern:

Be it known that I, Harry Chalfin, a citizen of the United States and a resident of the city of New York, in the county of Kings and State of New York, have invented a new, original, and ornamental Design for a Decorative Nail, of which the following is a specification, reference being had to the accompanying drawing, forming a part thereof.

Fig. 1 is a top elevational view of the decorative nail showing my new design; and

Fig. 2 is a side elevational view of the decorative nail shown in Fig. 1.

I claim:

The ornamental design for a decorative nail, substantially as shown.

HARRY CHALFIN.
